CLAIM

The ornamental design for a drop light, as shown and described.

DESCRIPTION

FIG. 1 is a front perspective view of a first embodiment of a drop light embodying my new design;
FIG. 2 is a rear perspective view of the drop light of FIG. 1;
FIG. 3 is a front view of the drop light of FIG. 1;
FIG. 4 is a rear view of the drop light of FIG. 1;
FIG. 5 is a first side view of the drop light of FIG. 1;
FIG. 6 is a second side view of the drop light of FIG. 1;
FIG. 7 is a top view of the drop light of FIG. 1;
FIG. 8 is a bottom view of the drop light of FIG. 1; and,
FIG. 9 is a cross-sectional view of the drop light of FIG. 1. The broken lines show portions of the article not claimed and form no part of the claimed design.
